FIG. 1

FIG. 2

FIG. 3

FIG. 4

FIG. 5

FIG. 6

1

SEAMLESS MALE GARMENT

TECHNICAL FIELD

This invention relates generally to male garments, and men's and boy's undergarments in particular and methods of manufacture.

BACKGROUND

Conventional men's undergarments, such as men's briefs, can be uncomfortable for the wearer and exhibit low breathability. An improved male undergarment would be desirable.

SUMMARY

According to one aspect of the present disclosure there is provided a seamless male undergarment including an integral fabric pouch for male genitalia.

According to another aspect of the present disclosure there is provided a seamless male garment including a front panel and a rear panel joined together forming a crotch area and legs, and an integrally molded pouch formed in the front panel to enclose male genitalia, wherein the breathability of the pouch is greater than the rest of the front panel and the back panel. The garment may be a male undergarment such as male underwear.

According to another aspect of the present disclosure there is provided a method of forming a pouch in male garment made from a synthetic composite fabric, the method including providing a die comprising a cup-shaped male component and a corresponding cup-shaped female component, stretching a front panel of the male garment over the male component to increase the diameter of the holes in the composite fabric and then pressing the stretched front panel with the female component with heat being applied to the front panel. The garment may be a male undergarment such as male underwear.

DRAWINGS

Various embodiments of the present invention will now be described with reference to the drawings, in which:

FIG. 1 is a front perspective view of a seamless male undergarment according to an embodiment of the present invention;

FIG. 2 is side perspective view of the seamless male undergarment of FIG. 1;

FIG. 3 is bottom view of the seamless male undergarment of FIG. 1;

FIG. 4 is a front view of the seamless male undergarment of FIG. 1;

FIG. 5 is a rear view of the seamless male undergarment of FIG. 1; and

FIG. 6 is bottom perspective view of the seamless male undergarment of FIG. 1;

DETAILED DESCRIPTION

Referring to the figures, an undergarment according an embodiment of the present invention are fabricated from a front panel 2 and the rear panel 4 of material. The ends of the front and rear panels are overlapped at the sides and the overlapped region is fused using an adhesive to form sutureless joins. The joins stretch vertically to move with the body unlike seams made with sutures.

2

The front 2 and rear 4 panels are joined together in the crotch area in indicated generally at 6. The legs 8 and 10 of the undergarment have a hem formed of a band of fabric upturned on the inside of the legs and sealed with an adhesive. The waist includes an elasticized waist band 12. The upper ends of the front and rear panels are folded over the waist band and heat sealed to enclose the waist band. This provides a seamless waist band which mitigates irritation caused by waist band chafing against the wearer's skin. 10 It also helps to mitigate wear and breakage of the waist band.

The undergarment includes an integrally molded pouch 14 in the front panel to enclose male genitalia and to provide comfort to the wearer. The absence of seams between the pouch and the front panel prevents chafing caused by 15 sutured seams. The breathability of the fabric forming the pouch is greater than that of the rest of the front panel and the back panel. In one embodiment, the fabric is a synthetic composite fabric of approximately 86% Creora® Polyamide and approximately 14% Spandex® or Lycra®. In one 20 embodiment, the fabric includes elongated nano fibres where the fibres that make up each thread are longer than in conventional materials which allows for greater strength and stretch recovery. In another embodiment, the fabric is made using a conventional polyamide weave that is transformed to 25 a statin weaved and thinned out. The present inventor refers to the satin weave material as Stealthweave™. In another embodiment, the synthetic fabric has a thickness in the range of 0.0045-0.0048 mm. In certain embodiments, the composite fabric forming the pouch has a fabric matrix with 30 approximately 0.25 mm diameter holes, 0.05 mm diameter holes, or in the range of 0.025 mm-0.05 mm diameter holes, in between warp and filament yarn, whereas the rest of the front panel, as well as the rear panel, has a fabric matrix with approximately 0.01 mm diameter holes, 0.1 mm diameter 35 holes, or in the range of 0.01 mm to 0.1 mm diameter holes in between warp and filament yarn. The holes serve as aeration holes. A spacing of 0.01 mm for the panels and 0.025 mm for the pouch is suited for sports activities underwear, while a spacing of 0.05 mm in the pouch is suited 40 for recovery underwear. The higher spacing provides greater breathability, airflow, and humidity and heat dissipation from the groin to cool the male genitalia to an optimal temperature range, while at the same time providing adequate support for the wearer's genitalia. This promotes 45 sperm health.

Prior to assembly, the fabric is heat pressed on steel rollers to improve the softness of the fabric and to reduce the coefficient of friction which reduces chafing against the wearer's skin.

50 The pouch is formed in the front panel prior to assembly using a die molding method. The mold is made of brass and includes cup-shaped male and female components in a die press. To mold the pouch, the front panel is stretch over the male component which increases the diameter of the holes, 55 and then pressed with the female component with heat being applied. The pouch is then cooled fixing the size of the aeration holes. The size of the aeration holes can be controlled by the degree of stretching applied to the fabric when stretched over the male component.

60 In another embodiment, the elastic waistband 12 is omitted and replaced by a polypropylene elastomer. The elastomer is applied in liquid form to the fabric at the waist using double sided tape to the waist of the underwear and allowed to harden on the fabric and the tape is peeled off. In one 65 embodiment, the elastomer forms a waistband ribbon 1.5 cm wide and 0.3 mm thick on the waist of the underwear. Such an elastomer waistband is more durable than conven-

tional elastic waistbands. In one embodiment, the elastomer waist is 50% thinner than a conventional elastic waist band and the breakage and warping associated with conventional elastic waist bands is avoided.

What is claimed is:

1. A seamless male garment comprising:

a front panel and a rear panel joined together forming a crotch area and legs, the front panel and the rear panel formed from a synthetic composite fabric; and an integrally molded pouch formed in the front panel to 10 enclose male genitals when worn, wherein

the synthetic composite fabric forming the front panel other than an area of pouch, and the rear panel, includes a fabric matrix with holes in a first range of 0.01 mm to 0.024 mm diameter holes, in between 15 warp and filament yarn,

the synthetic composite fabric forming the pouch includes a fabric matrix with holes having a diameter in a second range of 0.025 mm to 0.05 mm in between warp and filament yarn different from the 20 first range, such that a breathability of the pouch is greater than that of the front panel other than the area of the pouch, and the rear panel, and

the synthetic composite fabric comprises 86% poly- 25 amide and 14% elastane fabric.

2. The garment of claim 1, wherein the composite fabric has a thickness in the range of 0.0045-0.0048 mm.

3. The garment of claim 1, wherein the composite fabric comprises elongated nano fibres.

4. The garment of claim 1, wherein the composite fabric comprises a polyamide weave that has been transformed to 30 a satin weave and thinned out.

5. The garment of claim 1, further comprising a waist formed of a polypropylene elastomer applied to the synthetic composite fabric.

6. A garment comprising:

a front panel and a rear panel joined together forming a crotch area and legs, the front panel and the rear panel formed from a synthetic composite fabric; and an integrally molded pouch formed in the front panel to enclose male genitals when worn, wherein the pouch is formed using a die molding method using a die comprising a cup-shaped male component and a corresponding cup-shaped female component, and further comprising stretching the front panel over the male component to increase the diameter of the holes in the synthetic composite fabric forming the pouch and then pressing with the female component with heat being applied,

the synthetic composite fabric forming the front panel other than an area of pouch, and the rear panel, includes a fabric matrix with holes in a first range of 0.01 mm to 0.024 mm diameter holes, in between warp and filament yarn,

the synthetic composite fabric forming the pouch includes a fabric matrix with holes having a diameter in a second range of 0.025 mm to 0.05 mm in between warp and filament yarn different from the first range, such that a breathability of the pouch is greater than that of the front panel other than the area of the pouch, and the rear panel, and

the synthetic composite fabric comprises 86% poly- amide and 14% elastane fabric.
